UNITED STATES PATENT OFFICE

2,533,576

ROTARY KNOCKOUT MECHANISM FOR
PIG-CASTING MACHINESLeo A. Gonet, Duluth, Minn., assignor to The
American Steel and Wire Company of New
Jersey, a corporation of New Jersey

Application December 24, 1947, Serial No. 793,595

4 Claims. (Cl. 22—62)

1

This invention relates to apparatus for insuring the dislodgment of pigs of metal from the molds of a continuous pig-casting machine.

Metal from smelting furnaces such as the conventional iron blast-furnace is commonly disposed of by pouring it into the molds of a continuous pig-casting machine. Such machines are well known, usually comprising a plurality of pig molds extending between a pair of parallel chains traveling around spaced sprockets. A pouring ladle adjacent one end of the machine fills the molds successively. Most of the pigs thus cast fall out of the molds as they travel around the sprocket at the other end of the machine, but an occasional pig will stick in the mold despite the precaution usually taken of spraying the molds with a lime wash before each casting, to prevent sticking. When a pig fails to fall from the mold at the delivery end of the machine, it may fall at some point along the lower run of the chain with the possibility of damage to the machine parts or injury to personnel. In such case, the pig must be manually recovered and returned to the delivery end. If the pig remains in the mold until it is carried back to the pouring end of the machine, it will cause the molten metal to overflow the mold occupied by the sticking pig unless the pouring ladle is operated to stop the stream which supplies the molds. This results in costly delays and permits additional skulling of metal in the ladle. The overflow of molten metal may stall the chain drive or cause breakage of the chains.

Several forms of apparatus have been proposed for removing pigs from the molds of pig-casting machines but numerous objections to the use thereof have been encountered. It is the general object of my invention, therefore, to improve upon the means suggested previously for this purpose and to provide apparatus which is simple, inexpensive and highly efficient without requiring supervision or maintenance. Despite the prior devices for removing pigs, a sledge hammer has remained the most effective means for doing the job though at the expense of considerable manual labor. It is a further object of my invention, therefore, to provide power-driven means for delivering a succession of impact blows on the bottoms of the pig molds as they descend around the sprockets at the discharge end of the casting machine where all the pigs should fall out unless they adhere abnormally to the mold. A still further object is to provide means for delivering a measured blow to the molds so as to test their susceptibility to break-

2

age as a result of heat cracks, in addition to dislodging pigs therefrom. It is generally accepted that a mold which breaks when cold under a blow from a 12 pound sledge, because of such cracks, has reached the limit of its useful life. Still another object is to provide pig-dislodging mechanism which is entirely enclosed within the sprockets at the discharge end of the casting machine.

In a preferred embodiment of the invention, I mount a plurality of pivot pins for rotation with the sprockets for the mold chains at the discharge end of the machine. Conveniently, the pins are carried by one or more spiders mounted on the shaft supporting the sprockets and having radially projecting legs. Hammers are pivoted to said pins so that, on rotation of the sprockets, the hammers will be successively lifted up and carried over the shaft in back-swinging position. Then when their center of gravity moves ahead of the pivot pins, the hammers will fall forward on the descending side of the sprockets and strike the bottoms of the molds successively. The hammers are preferably composed of web plates having weights attached to their free ends. A pair of spiders may be employed and should have their legs in staggered relation.

A complete understanding of the invention may be obtained from the following detailed description which refers to the accompanying drawings illustrating a present preferred embodiment. In the drawings:

Figure 1 is a partial horizontal section through the sprocket shaft at the discharge end of a pig-casting machine;

Figure 2 is a partial vertical section taken on line II—II of Figure 1;

Figure 3 is a plan view showing a pair of hammer-supporting spiders, the hammers being omitted for clearness;

Figure 4 is a side elevation of the spiders showing the hammers attached to some of the spider legs only;

Figure 5 is an elevation showing an assembly of hammers pivoted to each leg of the spiders; and

Figure 6 is an end view of the hammer assembly on a leg of one of the spiders, showing in dotted lines the relative location of the hammer assembly carried by a leg of the other spider.

Referring in detail to the drawings, a plurality of pig molds 10 extend between a pair of parallel chains and are secured in groups to the links 11 thereof by bolts 12. The chains are maintained in proper relation to each other by spacer

rods 13 secured to the links and having rollers 14 on the outer ends thereof. At the delivery end of the machine, the chains travel around sprockets 15 mounted in spaced relation on a shaft 16, usually the head-shaft of the continuous chain conveyor provided by the molds 10 and links 11. The sprockets have teeth spaced circumferentially thereof provided with pockets 15^a adapted to accommodate the rollers 14 on the spacer bars 13. The shaft is journaled in suitable bearings, not shown, and is driven by any suitable means, such as an electric motor through appropriate reduction gearing. The elements of the structural framework supporting the upper and lower runs of the chain between the head-shaft and tail-shaft have been omitted, as well as the tail-shaft itself and the sprockets thereon since this construction is generally well known and no detailed disclosure thereof is necessary.

It will be understood that the sprockets 15 are driven in the counter-clockwise direction, as viewed in Figure 2, and that the mold-supporting chains travel in the direction indicated by the arrow. The molds are successively filled by a pouring ladle, in the customary manner at the pouring end of the machine, i. e., the end adjacent the tail-shaft. By the time the molds reach the vicinity of the sprockets 15 the pigs cast therein have solidified and should fall freely from the molds as the latter are inverted in passing around the sprockets. In order to insure that each mold is freed of its pig, I mount a spider 17 on the shaft 16, intermediate the sprockets 15. The spider has a hub 18 and circumferentially spaced arms projecting radially therefrom. Conveniently, a pair of spiders 17, 17^a are provided, as clearly shown in the drawings, with their hubs integral and the legs of one staggered between the legs of the other. The dual-spider structure is split transversely through its axis and is clamped to the shaft 16. It is secured thereon by bolts 20 and is keyed thereto so as to rotate with the shaft and sprockets, as shown in Figure 2. One of the legs 19 of one spider or the other is in radial alignment with each of the spacer bars 13 whose rollers are engaged by the sprocket teeth. The legs 19 of the spiders are slotted at their outer ends and are drilled to accommodate pivot pins 21. The bottoms of the slots at the ends of the spider legs are inclined to the radius through the legs as indicated at 22. The legs are also drilled to accommodate fixed bearing pins 23, the purpose of which will appear shortly.

Each leg of the spiders is provided with an assembly of three hammers 24, 25 and 26, as best shown in Figures 5 and 6. The hammers are pivoted on the pins 21 and hang vertically or remain in the lowest possible position permitted by their engagement with associated parts. Each hammer comprises a web plate 27 drilled and bushed to receive one of the pins 21 and a head portion 28 of increased thickness adapted to deliver an impact blow. The additional weight and thickness of the head portions may conveniently be provided by welding extra thicknesses of plate to the web plates 27. As shown in Figure 6, the hammers 24 and 26 are disposed on opposite sides of the spider leg 19 while the hammer 25 is fitted into the slot in the end thereof.

The positions successively assumed by the hammers of the several assemblies as the legs on which they are pivoted pass through their various positions are illustrated in Figure 2. It will be apparent from this showing that the hammers hang freely from the spider legs on the ascending

side of the sprockets. As the pin on which any given set of hammers are pivoted passes over the top of its circular path, the hammers swing back as far as permitted by the other elements of the structure, i. e., the web plate of the hammer 25 engages the bottom of the slot in the spider leg and the web plates of the hammers 24 and 26 engage the projecting ends of the bearing pin 23 in the same spider leg. The hammers thus pass from a vertical position to a backwardly inclined tangential position, through a horizontal position and then reach a position in which they are forwardly inclined with the head portions up-raised.

Eventually, as rotation of the shaft 16 proceeds, the center of gravity of each hammer will pass the dead-center position with respect to the pivot pin 21 after which the hammer will fall freely until it strikes the bottom of one of the pig molds. As indicated by the solid line positions of the hammers shown in Figure 2, one hammer strikes the bottom of each of the three molds secured to each pair of opposite links 11 of the mold-supporting chain. In this way, as each set of three molds moves around the sprockets 15 toward the fully inverted position, the molds are struck individually by the head portions of the freely falling hammers. The resulting impact blows effectively dislodge the pigs from the molds despite any tendency they might have to adhere thereto.

It will be appreciated that the spiders move in unison with the sprockets and chains so that proper cooperation of the hammers with the individual molds is maintained at all times. It will further be apparent that, since the rotary spiders carrying the hammer systems are mounted on the head shaft of the conveyor system, no separate drive or auxiliary power mechanism therefor is required. A further advantage of the invention is that, since the spiders rotate at a predetermined speed and the hammers fall through predetermined arcs before striking the pig molds, they deliver blows of a predetermined force to the latter. The several hammers of each assembly are preferably so proportioned that they deliver substantially equal blows. It will be noted that the hammer 24, which is the shortest of the three, has a heavier head portion than the others and that, similarly, the head portion of the intermediate length hammer 25 is heavier than that of the hammer 26 having the greatest length. The hammers are preferably so designed as to deliver a blow which will result in breakage of any mold which is cracked by heat-checking, warpage or the like to an extent such that it should be replaced.

The invention also has the advantages of simplicity, low cost and automatic operation without supervision or maintenance. In addition, the apparatus is enclosed between the sprockets and is thus in an out-of-the-way position requiring no additional floor space. Finally, the hammers deliver sufficient impact to the bottoms of the upturned molds to insure dislodgement of any pig which tends to stick in the mold, thus preventing the undesirable results pointed out above which occur when a pig fails to drop out and is carried back to the pouring end of falls from the mold while the latter is traversing the lower run of the chains.

Although I have illustrated and described but a preferred embodiment of the invention, it will be recognized that changes in the details of the construction disclosed may be made without de-

parting from the spirit of the invention or the scope of the appended claims.

I claim:

1. In a pig-casting machine including spaced traveling chains, a shaft having sprockets thereon around which the chains are trained and molds extending between the chains, the combination therewith of pig-dislodging means comprising a spider secured to said shaft between the sprockets having a plurality of radial legs, and a plurality of hammers of different lengths pivoted adjacent the end of each leg whereby, on rotation of the shaft, the hammers fall forward on the descending side of the sprockets and strike the molds successively.

2. The apparatus defined by claim 1, characterized by a pin projecting laterally from each leg of the spider adapted to support the hammers in back-tilted position as the legs pass over the top of their path on rotation of the spider.

3. In a pig-casting machine including spaced traveling chains, a shaft having sprockets thereon around which the chains are trained and molds extending between the chains, the combination therewith of pig-dislodging means comprising a member secured to the shaft between the sprockets, a plurality of pivots spaced circumferentially of said member and a plurality of

hammers of different lengths journaled on each pivot whereby, on rotation of the shaft, the hammers fall forward on the descending side of the sprockets and strike the molds successively.

5 4. The apparatus defined by claim 3 characterized by each of said hammers including a web plate having its thickness increased adjacent the outer end to provide a head portion.

LEO A. GIONET.
